US0D1042448S

(12) **United States Design Patent** (10) **Patent No.:** **US D1,042,448 S**
(45) **Date of Patent:** **** Sep. 17, 2024**

(54) **COMMUNICATION DEVICE**

(71) Applicant: **Moxa Inc.**, New Taipei (TW)

(72) Inventors: **Min-Heng Yao**, New Taipei (TW);
Sung-Wei Chou, New Taipei (TW)

(73) Assignee: **Moxa Inc.**, New Taipei (TW)

(**) Term: **15 Years**

(21) Appl. No.: **29/890,627**

(22) Filed: **Apr. 25, 2023**

(30) **Foreign Application Priority Data**

Mar. 31, 2023 (TW) 112301585

(57) **CLAIM**

The ornamental design for a communication device, as shown and described.

DESCRIPTION

FIG. 1 is a top, front, right side perspective view of a communication device, showing our new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, right side perspective view of the communication device of FIG. 1, shown in another condition of use; and,

FIG. 10 is a bottom, rear, left side perspective view thereof. The broken lines in the drawings and the lightened areas within the broken lines represent portion of the communication device that form no part of the claimed design.

1 Claim, 10 Drawing Sheets
